UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

SLIP.

Application filed September 3, 1924. Serial No. 735,656.

To all whom it may concern:

Be it known that I, TAUBE DAVIS, a citizen of the United States, and a resident of the city of New York, borough of Manhattan, in the county and State of New York, have invented a new and Improved Slip, of which the following is a full, clear, and exact description.

This invention relates to slips designed for women's wear, an object of the invention being to provide a slip which presents straight lines, which is relatively narrow but which insures comfort in walking and in sitting.

A further object is to provide a slip which is composed of two straight pieces of material constituting front and back portions of the garment, the seam lines being located at the side rear portions of the garment, and plaits are formed in the garment extending throughout the length thereof, the plaits being closed from a point adjacent the waistline to the top of the garment, and open throughout the lower portion of the garment so as to allow the garment to expand in walking or sitting and to lie in straight lines when the user is in a standing or upright position.

With these and other objects in view, the invention consists in certain novel features of construction and combinations and arrangements of parts which will be more fully hereinafter described and pointed out in the claim.

In the accompanying drawings—

Figure 1 is a perspective view illustrating a figure on which my improved slip is shown;

Figure 2 is an enlarged view, in section, of the garment, the view being taken on the line 2—2 of Figure 1;

Figure 3 is a similar view in section on the line 3—3 of Figure 1.

In constructing my improved slip I provide front and rear pieces 1 and 2 which are of general oblong shape and plan and extend throughout the length of the garment. The front piece 1 is preferably wider than the rear piece 2, and said pieces are connected by longitudinal seams 3. These seams, it will be noted, are at the side rear portions of the garment.

The garment may be supported on the figure by shoulder straps 4 or other suitable supporting devices, to which, of course, the invention is not limited.

The front piece 1 is provided at its edges and at the sides of the garment with folded plaits 5. The edges of these plaits are secured to the garment and, preferably, to the seams 3 of the garment, from a point adjacent the waist line of the garment to the top of the garment. The other portion of the plaits from a point adjacent the waistline to the bottom of the garment are open or unconnected so that the garment can expand at its lower portion to permit comfort in walking and not bind the legs, and also permit comfort when in a sitting posture. As soon as the figure assumes an upright position the plaits will naturally close and the slip will give a perfect straight line appearance.

A garment of this kind can be manufactured and sold at a reasonably low price, will conform to the mode, and will give the desired straight lines and yet not unduly restrict the movement of the legs of the user.

Various slight changes and alterations might be made in the general form of the parts described without departing from my invention, and hence I do not limit myself to the precise details set forth but consider myself at liberty to make such slight changes and alterations as fairly fall within the spirit and scope of the appended claim.

I claim:

A slip of the character described, comprising front and rear pieces of general oblong shape, the front piece being appreciably wider than the rear piece, said pieces connected by seams extending throughout the length of the garment, plaits formed in the front piece of the garment at the sides thereof and extending throughout the length of the garment, said plaits closed and having their edges secured to the seams of the garment from a point adjacent the waistline of the garment to the upper end of the garment.

TAUBE DAVIS
